INVENTOR
Theodore H. Fishel

BY
George W. Williams
ATTORNEY

UNITED STATES PATENT OFFICE.

THEODORE H. FISHEL, OF NEW ROCHELLE, NEW YORK.

JEWELRY.

1,194,611.

Specification of Letters Patent. Patented Aug. 15, 1916.

Application filed October 30, 1915. Serial No. 58,773.

To all whom it may concern:

Be it known that I, THEODORE H. FISHEL, a citizen of the United States, residing at 14 Manhattan avenue, New Rochelle, in the 5 county of Westchester and State of New York, have invented certain new and useful Improvements in Jewelry, of which the following is a specification, reference being had therein to the accompanying drawings, 10 forming part thereof.

My invention relates broadly to improvements in articulated ornaments and more particularly to articles of jewelry such as bracelets, chains and the like.

15 An object of my invention is to provide in such articles smooth even sides together with a necessary amount of flexibility.

A further object of my invention is to provide means for joining individual jewel settings so as to present a continuous line of 20 jewels to the eye and at the same time have the sides and back of the settings form practically flush lines.

Another object herein is to provide means 25 for joining jewel settings where little or no metal is presented to the eye on the surface in which the jewels are set, such jewels being usually colored and not depending on their setting for their brilliancy.

30 Another and further object of my invention is to join integral sections or links without the use of separate connecting means.

Further objects of my invention are simplicity, strength, inexpensiveness and 35 facility and ease of manufacture.

My invention has other features and advantages which will appear from the following description.

I will now describe the embodiments of 40 my invention illustrated in the accompanying drawings and will thereafter point out my invention in claims.

Figure 1 is a view in perspective of a bracelet embodying my invention. Fig. 2 45 is a rear view of three sections of the bracelet shown in Fig. 1. Fig. 3 is a central longitudinal section taken on the line 3-3 of Fig. 2. Fig. 4 is a view in perspective of a single section or link containing no jewel.

50 The bracelet embodying my invention shown in Fig. 1, consists of a succession of sections or links 1 joined so as to make the sides and backs of the sections practically contiguous and at the same time maintain 55 flexibility between the links.

The link 1 is integral and is formed by stamping it from a sheet of suitable metal. It has a back 2 and two side walls 3, the other two sides being open. A tongue or projection 5 is formed at one of the open 60 sides of the link 1. At the other open side there is another projection 6 having therein a perforation and forming a loop or eye 7, for the purpose hereinafter explained.

In joining the sections, (as is best shown 65 in Fig. 3) the tongue 5 of one link is adapted to be inserted from the under side into the loop or eye 7 in the adjacent link, the end of the tongue being then folded around the projection 6 allowing enough room for 70 it to move freely in such position. The projection 6 is raised above the bottom of the back 2 a distance equal approximately to the thickness of the back, and projection 6 of one link slightly overlaps the upper side of the 75 back 2 of the adjacent link. This serves not only to strengthen the joint but also makes a smooth and even backing, and at the same time the means by which the links are joined 80 is concealed when the jewel is put in the setting. The joint is flexible and allows considerable pivotal movement of the links about the projection 6.

A shoulder 9 is formed on the inside of each side wall 3, the upper portion of the 85 wall 4 above the shoulder 9 being thinner than the lower portion. The shoulders 9 on the opposite side walls 3 form a jewel-receiving socket. A jewel 8 is adapted to be placed in the section or link and rest on 90 the shoulders 9, the upper portions 4 of the side walls being then slightly crimped or bent over the edges of the jewel 8 to hold it in place, the jewel being held on two sides only. The jewel 8 is rectangular and 95 of approximately the same length and breadth as the link 1.

In connecting the links, the side walls 3 of the adjacent links come together, and likewise the edge 10 of one jewel is practically in contact with the edge 11 of the adjacent jewel so that to the eye there is presented a continuous line of jewels having only a very narrow outer margin of metal, consisting of the upper wall portions 4 holding the jewels in place.

The article is made of any desired number of sections joined as hereinbefore described and any suitable connecting means may be provided for joining the ends there- 110

of, such for example, as the spring catch 12 and chain 13 shown in Fig. 1.

It is obvious that various modifications may be made in the construction shown and above particularly described within the principle and scope of my invention as set forth in the following claims.

I claim:

- 10 1. An integral jewel setting adapted to receive and hold a jewel on two sides, consisting of a back, two side walls and two open sides, a tongue formed at one of the open sides and a loop formed at the other open side.
- 15 2. An integral jewel setting consisting of a back, two side walls and two open sides, a tongue formed at one of the open sides and a loop formed at the other open side, the loop being slightly raised above the bottom 20 of the jewel setting.
3. An integral jewel setting consisting of a back, two side walls, each having on its inner side a shoulder on which a jewel is adapted to rest, and two open sides, a tongue

formed at one of the open sides and a loop 25 formed at the other open side.

4. An article of jewelry consisting of sections flexibly connected, each section having a tongue at one end and a loop at the other end, the tongue of one section being adapted to fit into from the bottom and fold over the loop in the adjacent section, the connecting means being concealed by the jewels placed in the sections.

5. An article of jewelry consisting of in 35 integral sections flexibly connected, each section being adapted to receive a jewel, the sections being connected closely together so that the jewels form a practically continuous line and are held in position by the side 40 walls of the sections, each section having a tongue at one end and a loop at the other end, the tongue of one section being adapted to fit into and fold over the loop of the adjacent section.

In testimony whereof I have affixed my signature.

THEODORE H. FISHEL.
